CLAIM

The ornamental design of a pipe clamp, substantially as shown and described.

DESCRIPTION

FIG. 1 is a perspective view of a pipe clamp showing our new design;

FIG. 2 is a front elevational view thereof in use with a pipe and channel;

FIG. 3 is a right side elevational view thereof in use with a pipe and channel;

FIG. 4 is a rear elevational view thereof in use with a pipe and channel;

FIG. 5 is a left side elevational view thereof in use with a pipe and channel;

FIG. 6 is a top plan view thereof; and,

FIG. 7 is a bottom plan view thereof.

The broken line showing of a screw aperture, pipe, and channel is included for the purpose of illustrating environment and forms no part of the claimed design.
